UNITED STATES PATENT OFFICE.

ISIDOR HEYMANN, OF NEW YORK, N. Y.

DESIGN FOR A PURSE.

SPECIFICATION forming part of Design No. 17,107, dated February 8, 1887.

Application filed October 30, 1886. Serial No. 217,637. Term of patent 7 years.

To all whom it may concern:

Be it known that I, ISIDOR HEYMANN, of the city, county, and State of New York, have invented a new and original Design for a Purse, of which the following is a description, reference being had to the accompanying drawings, forming thereof a part.

Figure 1 is a perspective view of my newly-designed purse closed. Fig. 2 is a perspective view of the same opened.

The leading feature of my design consists in a cap of suitable shape, forming the body of the purse. One side, A, of the body portion of the purse is enlarged and shaped after the manner of the crown of the German military cap, the other side, B, of the purse-body being

flat, as usual. The flap B', carried by the part A of the body, is shaped to conform to the peak of the cap, the flap B" being shaped in the ordinary manner, so that the purse, when closed, presents the exact appearance of the complete cap.

I claim—

The design for a purse herein shown and described, the same consisting of a peaked cap, the peak of which is represented by the purse flap or flaps.

ISIDOR HEYMANN.
